TENTERING MACHINE

John E. Peterson, Irvington, N. J., assignor to
Van Vlaanderen Machine Company, Paterson,
N. J., a corporation of New Jersey

Application July 16, 1931. Serial No. 551,129

7 Claims. (Cl. 26—57)

This invention relates to machines, known as tentering machines or tenters, in which cloth, while conveyed lengthwise by and between two travelling endless chains comprising clips to grip the edges of the cloth, is stretched transversely by the chains which, after receiving the cloth in their clips, undergo divergence from each other. In these machines each chain is engaged with a driving and an idler sprocket and is supported between them by a rail and the two such rails are adjustable toward and from each other to provide for tentering cloth in different widths. The principal objects of this invention are to provide for a more substantial and rigid support of the rails by what I term the main frame at the output end of the machine and to insure the movability of each rail toward and from the other on said frame with less tendency than heretofore to cramp or bind; to provide means whereby the actuation necessary to space the rails as required may be derived from the same transverse shaft as that by which the driving sprockets are driven, though subject to manual control, such means being so designed as to be more compact, reliable and efficient and also more easily controlled than heretofore; to provide means whereby the spacing of the rails may be gaged and hence accurately and easily determined; and to provide for housing the means to drive said shaft in a simple and practical way.

In the drawings,

Fig. 1 is a right side elevation of the power end of the machine;

Fig. 2 is a fragmentary plan thereof;

Fig. 3 is a view in vertical longitudinal section through the girt 3 and showing how the power is transmitted from the drive shaft to the main shaft 17;

Fig. 4 is a section on line 4—4, Fig. 2;

Fig. 5 is a view somewhat similar to Fig. 2 but on a larger scale and showing the mechanism of the unit whereby power is transmitted from shaft 17 for moving the chain rail structures toward or from each other; and,

Figs. 6, 7 and 8 are sectional views on lines 6—6, 7—7 and 8—8 of Figs. 5, 6 and 7, respectively.

1 and 2 denote two side standards connected by a girt 3 which seats at one end in a recess 1a of standard 1 and may be bolted thereto and which has its other end abutting and may be bolted to standard 2, the standards being preferably connected by tie-rods 4. A rigid and strong frame, which I term the main frame, is thus formed and, as will be seen, since the chain rail structures overhang the girt and are seated there-

on, this construction avoids elevating the rail structures at a height inconvenient to the attendant.

Seated upon the top surface of the girt which is machined off so as to present lengthwise straight surfaces 3a and slidably lengthwise thereof are two boxes 5 each having depending flanges 5a which bear against the opposite sides of the girt so that their sliding movement is confined to the rectilinear. These boxes form depending portions of the near ends of the chain rail structures, in fact supporting the ends of the rails proper and also the sprockets for driving the chains and the openers for the clips of the latter, thus:

Each box has a cover 6 flanged at 6a at its under side to retain it in place and seated thereon is the said end of the rail proper 7 secured thereto by screws 8. The cover is penetrated by a shaft 9 journaled at 10 and 11 and carrying a worm-wheel 12 within the box, a sprocket 13 above the rail and a circular clip-opener 14, all fixed to the shaft. It will be understood that each chain extends around one of the sprockets and a companion sprocket at the far end of the rail, as usual; the chain as a whole is not shown, but 15 designates one of the component clip-links thereof whose movable jaw 15a is adapted to be opened by the opener 14 when the clip passes around sprocket 13.

The two shafts 9, with the sprockets and openers, are rotated by worms 16 engaged with worm-wheels 12 and splined at 17a to the main shaft 17, journaled, as hereinafter stated, above and extending parallel with the girt 3 and (freely) through the boxes 5, the worms being contained in the boxes and confined to move therewith along the girt.

Heretofore the girt was a horizontally thin rail and the ends of the chain-rail structures, arranged at a level but slightly above the girt, were provided with depending apron-like portions inward of and which faced and bore against the vertical inner face of the girt and had gibbed overhangs in effect hooked over the top edge of the girt. This construction was neither substantial nor rigid and resulted in binding of the rail structures both as to the frame and as to the shaft, as 17, and involved undue expense to manufacture. In my construction the rail structures overhang at their ends and, through their boxes, are planted atop the girt, and so they may slide on the guideway formed at 3a without binding or cramping, the construction is less expensive and more readily assembled, and is exceed-

ingly strong and durable, and at the same time the rail structures are at the level convenient to the attendant.

The shaft 17 is driven by a sprocket-and-chain 5 means 18 (shown best in Fig. 3) contained within an inclined housing 2a forming part of the standard 2, the drive shaft 19 of the transmission thus provided being or being connected to the shaft of an electric motor 20 supported in any way, not 10 shown, inward of said standard; thus said transmission is housed within an already existing part of the main frame.

The two rail structures may be adjusted toward and from each other along the girt 3 by a screw 15 21 parallel with the shaft 17 and journaled as hereinafter stated and engaged with nuts 22 depending from the rail structures. This screw has right- and left-hand threads to engage the nuts of the two rails so that on rotation of the screw 20 one way or the other the motion of the rail structures will be toward or from each other.

The main shaft 17 and this screw are journaled in suitable bearings 17a and 21a, only those for the near ends of shaft and screw in Fig. 1 appearing 25 in Fig. 5, such bearings for said ends being here provided in a housing 24 which is fixed to the girt 3 and standard 1 and forms in effect a bearing support thereof. By mechanism within this housing the screw 21 is rotated one way or the other at the election of the attendant and from shaft 17 as the driver for adjusting the mentioned rail structures toward or from each other (Figs. 5 to 7) thus:

The main shaft has affixed thereto within the 35 housing a cone 25 with which is adapted to engage either of two cones 26 formed on a sleeve 27 which is journaled in and protrudes from the housing at right angles to the main shaft 17. (The sleeve is shown in Fig. 6 as formed in two 40 parts, one wholly within the housing and having the cones 26 and the other screwed fast into it and protruding from the housing.) This sleeve is splined at 27a on a worm-shaft 28 whose worm portion 28a, keyed or otherwise affixed thereto, is 45 journaled between thrust bearings 29 which confine it from endwise movement. Between thrust bearings 30 on the protruding part of the sleeve is a free collar 31 having diametric pins 31a with which engages the fork of a hand lever 32 ful- 50 crumed in the housing. Shaft 17 being in rotation, when the sleeve is shifted by the hand-lever one way or the other the worm-shaft is rotated one way or the other from cone 25 through one 55 of the cones 26. In the intermediate position of the sleeve it of course remains stationary. The worm 28a of the worm-shaft meshes with a worm-wheel 33 which is affixed to the screw 21. Thus, according as the lever is shifted one way or the other, the two rail structures will be shifted to- 60 ward or from each other by the power derived from the main shaft.

In order to gage the extent of such adjustment of the two rail structures apart I provide the following mechanism: A column 34 upstands from 65 cover 24a of a housing 24 and is affixed thereto, it having a vertical slot 34a and a scale 34b adjoining the same and provided with suitable indices. Contained within the column is a nut 35 having a stud or spline 35a which moves in said slot and 70 constitutes a pointer cooperative with the scale.

The nut 35 receives and is in threaded engagement with a screw 36 having a bevel pinion 37 which meshes with a bevel pinion 38 on the screw 21; screw 36 is confined against vertical play by 75 a collar 39 and a nut 39a at the lower and upper

ends of the column. By following the movement of the pointer relatively to the scale as he causes the rail structures to move apart or together in the way described the attendant can determine when the desired adjustment of such structures has been attained.

It will be understood that the rail structures reach some distance, as usual, from the main frame, and for this purpose they are supported and slideable on frames 40 arranged at intervals of their length. For imparting movement to said structures at such intervals which shall be in synchrony with that imparted thereto at their ends adjoining the main frame the construction is as follows: Coincident with each of the frames 40 said structures have nuts 41 engaged by right- and left-hand screws 42 parallel with screw 21. Journaled in housing 24 and 43 on said frames (i. e., the main frame and frames 40) is a shaft 44 extending lengthwise of said structures, and this is intergeared with the screw 21 by bevel gearing 45 and 46 and with the screws 42 by bevel gearing 47 and 48. Thus, when the screw 21 is rotated one way or the other to adjust the output end portion of the rail structures toward or from each other the screws 42 are correspondingly rotated with the result that said structures move at the same speed throughout their entire length.

The top surface of the standard 1 is about flush with the guideway 3a, thus forming therewith a surface on which not only are the rail structures slideable but the support (housing 24) for the means 28-28a and 33 for rotating screw 21 is mounted.

Having thus fully described my invention, what I claim is:

1. In a tenter, the combination of the main frame having a transverse horizontal girt formed with a wide lengthwise straight top guideway, a pair of chain-rails having their ends overhanging said guideway, rotary chain-driving elements revoluble in said ends with their axes vertical and having their axial portions depending from said ends and provided with gear members, boxes resting upon and having sliding engagement with said guideway and confined by the girt to slide along the guideway rectilinearly, said boxes supporting said ends of said rails and containing said gear members, a rotary shaft journaled parallel with the girt, and gear members splined on said shaft and intergeared with the first gear members and confined in and by the respective boxes to slide therewith along said shaft.

2. In a tenter, the combination of supporting structure, a pair of chain-rail structures slideable thereon toward and from each other, rotary chain-driving means journaled in said rail structures, a drive shaft journaled in said supporting structure transverse of the rail structures and geared with said means and having a beveled driving member, a screw journaled in the supporting structure parallel with the shaft and having screw-engagement with the rail structures, a revolute element journaled in said supporting structure transverse of the shaft and screw and geared with the screw, and a back-and-forth slideable element splined to the first element and having beveled driven members movable with the slideable element alternately into and out of engagement with said driving member.

3. In a tenter, the combination of fixed structure, a pair of chain-rail structures slideable thereon toward and from each other, means in said fixed structure to adjust the rail structures toward and from each other including a revolute

5 screw extending transversely of the rail structures, a part of said fixed structure having a scale, a nut confined by said fixed structure to move lengthwise of and having a pointer cooperative with the scale, and a screw journaled in the fixed structure parallel with the scale and geared with the first screw to rotate therewith and having screw-engagement with the nut.

10 4. In a tenter, the combination of fixed structure including a hollow column having a longitudinal slot and a scale parallel with the slot, a pair of chain-rail structures slidable on the fixed structure toward and from each other, means in said fixed structure to adjust the rail structures toward and from each other including a revoluble screw extending transversely of said rail structures, a nut in the column having a spline in the slot and cooperative with the scale as a pointer, and a screw extending longitudinally through the 15 20 column and journaled in the fixed structure and geared with the first screw to rotate therewith and having screw-engagement with the nut.

25 5. In a tenter, the combination of the main frame including standards and a girt rigidly connecting them, one of said standards forming a hollow housing, a pair of chain-rail structures slidable on the girt toward and from each other, rotary chain-driving means journaled in said rail structures, a drive shaft journaled in the frame 30 parallel with the girt and geared with said means, a rotary shaft from which to drive the drive

shaft, and transmission means between the latter shaft and drive shaft contained within the housing.

6. In a tenter, the combination of supporting structure including a main frame having a transverse guideway and a support secured upon the frame, a pair of chain-rail structures slidable along the guideway, rotary chain-driving means journaled in said structures, means to rotate the first means including a rotary shaft geared therewith and extending parallel with the guideway, and a revoluble screw arranged parallel with the shaft and having screw-engagement with said rail structures, said support affording bearings for both the shaft and the screw, and means carried by the support for transmitting rotation from the shaft to the screw. 80 85 90

7. In a tenter, the combination of supporting means, a pair of chain-rail structures laterally movable thereon, rotary chain-driving means journaled in said structures, means to rotate the latter means including a rotary shaft geared therewith, a revoluble screw having a screw-engagement with and adapted on rotation to move said structures, said shaft and screw extending 100 105 transversely of said structures and said supporting means including a housing in which end portions of the shaft and screw are journaled, and means in the housing for transmitting rotation from the shaft to the screw. 95
